UNITED STATES PATENT OFFICE.

FRANK O. GREEN, OF CHICAGO, ILLINOIS, ASSIGNOR TO LIBBY, McNEILL & LIBBY, OF CHICAGO, ILLINOIS, A CORPORATION OF MAINE.

DESIGN FOR A BOTTLE OR JAR.

52,952.

Specification for Design.

Patented Feb. 4, 1919.

Application filed August 26, 1918. Serial No. 251,593. Term of patent 14 years.

To all whom it may concern:

Be it known that I, FRANK O. GREEN, a citizen of the United States, residing at Chicago, in the county of Cook and State of Illinois, have invented a new, original, and ornamental Design for Bottles or Jars, of which the following is a specification, reference being had to the accompanying drawing, forming part thereof.

The figure is an elevation of the bottle or jar showing my new design.

I claim:

The ornamental design for a bottle or jar, as shown.

FRANK O. GREEN.
